UNITED STATES PATENT OFFICE

151,272

DESIGN FOR A TOWEL RACK

Karl Kipp, Olean, N. Y., assignor to Daystrom Corporation, Olean, N. Y., a corporation of New York

Application May 10, 1946, Serial No. 129,573

Term of patent 7 years

(Cl. D33—16)

To all whom it may concern:

Be it known that I, Karl Kipp, a citizen of the United States, residing at Olean, in the county of Cattaraugus and State of New York, have invented a new, original, and ornamental Design for a Towel Rack, of which the following is a specification, reference being had to the accompanying drawing, forming part thereof; and in which the figure is a perspective view of a towel rack, showing my new design.

I claim:

The ornamental design for a towel rack, substantially as shown.

KARL KIPP.
